UNITED STATES PATENT OFFICE.

WILFORD JUDSON HAWKINS, OF MONTCLAIR, NEW JERSEY.

PROJECTILE-FUSE.

1,216,802.

Specification of Letters Patent. Patented Feb. 20, 1917.

Application filed June 2, 1916. Serial No. 101,280.

To all whom it may concern:

Be it known that I, WILFORD JUDSON HAWKINS, a citizen of the United States, residing at Montclair, county of Essex, and State of New Jersey, have invented a new and useful

5 Improvement in Projectile-Fuses, of which the following is a specification.

This invention relates to an improvement in projectile fuses, either of the percussion or combination type, having for its main object the production of a simplified and durable means for positively holding the detonating mechanism in unarmed position until acceleration ceases, and then causing it to be released by the centrifugal force developed by the projectile in flight. With this and other objects not specifically mentioned in view, the invention consists in certain parts, constructions and combinations which 10 will be hereinafter fully described and then specifically set forth in the claims hereunto appended.

In the accompanying drawings, which form a part of this specification and in 25 which like characters of reference indicate the same or like parts, Figure 1 is a central sectional view of a device constructed in accordance with the invention; and Fig. 2 is a detail view of the plunger holding split 30 sleeve.

In carrying the invention into effect, there is provided a detonating plunger and a single member adapted for engaging and positively holding the plunger in unarmed position until projectile acceleration ceases and then to be disengaged from said plunger by the centrifugal force developed by the projectile in its flight. In the best constructions, the single member is normally carried 40 by the plunger and consists of a split sleeve surrounding the plunger and having a beveled edge adapted for engagement with an undercut flange formed on the plunger to prevent centrifugal force from causing the 45 expansion of the sleeve until after acceleration ceases. In the best constructions also, there is provided a plunger holding sleeve provided with a series of longitudinal grooves to form the sleeve into connected 50 segments, the weights of which are pre-determined in accordance with the rotative velocity of the projectile at the muzzle of a gun in connection with which it is to be used. In the best constructions also, there is provided 55 a projectile fuse having a two-part fuse body, one part carrying an integral

gaine. And in the best constructions also, there is provided a fuse body comprising two separable parts one of said parts carrying an integral gaine, and a detonating mechanism housed within the body.

All of the above elements may be varied in construction within wide limits. The device selected to illustrate the invention is but one of many possible concrete embodiments of the same. The invention therefore is not to be restricted to the precise details of the structure shown and described. Furthermore, certain parts of the invention are capable of use independent of other parts and such independent use is contemplated.

Referring to the drawings, 3 indicates a part of a fuse body which is provided with a thread 4 by means of which it is screwed into a projectile. The part 3 also has an integral gaine 5 provided in its interior with communicating chambers 6, 7 and 8 adapted for holding explosives. The gaine is further provided with internal threads 9 and 10 into which suitable plugs may be screwed. The gaine, as shown, is in stepped form because the particular device selected to illustrate the invention is especially adapted to fit existing projectiles in which the explosive charges are of a form corresponding with the stepped form of the gaine. It is however to be understood that a parabolic gaine contour (indicated by the broken lines 11) would be preferable, the explosive charges surrounding the gaine being formed in accordance therewith. Threaded at 12 into the forward end of the body part 3 is a second body part or cap 13. This cap is provided with an integral detonator striker 14 and has an internal chamber 15 in which is located a spiral spring 16. The body part 3 is provided with a chamber 17 one end of which is formed by the rear end of the cap 13. The spring 16 bears against the end of the chamber 15 and against a shoulder 18 formed upon a plunger 19 which is mounted to reciprocate within the chamber 15. This plunger is provided with a central aperture 20, the forward end of which is reduced in bore and shouldered to hold a detonator pellet 21. The detonator pellet 21 is held in position by means of a hollow sleeve, not shown, but which is adapted to be threaded at 22 into the plunger 19. The rear end of the plunger is provided with a flange 23 having an undercut forward face 23'. Surrounding the plunger between this flange

and the rear end of the cap 13 is a sleeve 24 which is split at 25 and provided with a series of internal longitudinal grooves 26. The rear end of the split sleeve is beveled at 27, the beveled end normally lying in engagement with the undercut flange 23 of the plunger.

By an inspection of Fig. 1, it will be noted that the split sleeve is not quite as long as the space between the plunger flange 23 and the rear end of the cap 13. The clearance space between the forward end of the split sleeve and the rear end of the cap 13 is for the purpose of providing clearance, so that at the proper time the sleeve may move forward far enough to permit its beveled end to clear the undercut flange 23 in expanding to plunger releasing position.

20 When the projectile carrying the fuse is fired from a gun, the plunger 19 and split sleeve 24 are set back hard by their inertia, if not already in that position. As the projectile moves down the rifled bore of the gun, centrifugal force is developed which tends to act upon the split sleeve 24 to cause it to open or expand out into the chamber 17 and clear of the plunger flange 23. This centrifugal force is less than the acceleration force, and therefore until acceleration ceases the interlocked engagement of the beveled rear end of the split sleeve 24 with the undercut flange 23 of the plunger will prevent the sleeve from expanding out of engagement with the plunger flange. It will therefore be readily noted that the detonating mechanism, of which the plunger is a part, is held positively in unarmed position until acceleration ceases. When acceleration ceases, the centrifugal force becomes greater than the force which until then held the beveled end of the sleeve and the undercut plunger flange in engagement. The sleeve is then opened out or expanded 45 by centrifugal force, climbing up and disengaging itself from the undercut flange and expanding into the chamber 17 clear of the plunger flange. The detonator mechanism is then armed and will come into operation when the projectile strikes an obstruction, the inertia of the plunger being at that time sufficient to insure the compression of the spring 16 and the engagement of the detonator pellet and striker.

50 The revolutions per minute of projectiles at the muzzles of different guns vary. The centrifugal force which may be developed to open or expand the sleeve 24 varies directly with the weight of the individual segments and inversely as the radius of the sleeve itself. The weights of the segments are therefore pre-determined in accordance with the rotative velocity of the projectile, as developed in a certain type of gun with a 60 certain charge of propelling explosive. If

the projectile is to be used under different conditions, the sleeve must be altered or another one substituted which is suitable for the different rotative velocity in order to maintain the highest efficiency.

70 What is claimed is:

1. In a projectile fuse, the combination with a fuse body, of a plunger within the body, and a single member in interlocked engagement with said plunger for holding said plunger in unarmed position until projectile acceleration ceases.

75 2. In a projectile fuse, the combination with a fuse body, of a plunger within the body, and a single member carried by and in interlocked engagement with said plunger for positively holding said plunger in unarmed position until projectile acceleration ceases.

80 3. In a projectile fuse, the combination with a fuse body, of a spring retained plunger within the body, and a single member in interlocked engagement with said plunger for positively holding said plunger in unarmed position until projectile acceleration ceases.

85 4. In a projectile fuse, the combination with a fuse body, of a cylindrical spring retained plunger within the body, and a single member carried concentrically by and in interlocked engagement with said plunger for positively holding said plunger in unarmed position until projectile acceleration ceases.

90 5. In a projectile fuse, the combination with a fuse body, of a cylindrical plunger within the body, and a split sleeve surrounding and in interlocked engagement with said plunger for positively holding said plunger in unarmed position until projectile acceleration ceases.

100 6. In a projectile fuse, the combination with a fuse body, of a cylindrical plunger having a flange within the body, and a split sleeve overlying and in interlocked engagement with the plunger flange for positively holding said plunger in unarmed position until projectile acceleration ceases.

105 7. In a projectile fuse, the combination with a fuse body, of a plunger having an undercut flange within the body, and a split sleeve having a beveled end adapted for engaging the undercut flange and positively holding said plunger in unarmed position until projectile acceleration ceases and then to be disengaged from said plunger by centrifugal force.

110 8. In a projectile fuse, the combination with a fuse body, of a plunger within the body, and a split longitudinally grooved sleeve surrounding and in interlocked engagement with said plunger for positively holding said plunger in unarmed position until projectile acceleration ceases.

115 9. In a projectile fuse, the combination

- with a fuse body in two parts one part carrying an integral gaine, of a plunger within the body, and a single member in interlocked engagement with said plunger for 5 positively holding said plunger in unarmed position until projectile acceleration ceases.
10. In a projectile fuse, the combination with a fuse body carrying an integral detonator striker, of a plunger within the body carrying a detonator pellet, and a single member in interlocked engagement with said plunger for positively holding said plunger in unarmed position until projectile acceleration ceases.
15. 11. In a projectile fuse, the combination with a fuse body in two parts one part carrying an integral gaine and the other part carrying an integral detonator striker, of a plunger within the body carrying a detonator pellet, and a single member in interlocked engagement with said plunger for positively holding said plunger in unarmed position until projectile acceleration ceases.
12. In a projectile fuse, the combination 25 with a fuse body comprising two separable parts one of said parts carrying an integral gaine, of a detonating mechanism housed within said body and comprising a detonator pellet, a coöperating plunger, and a single 30 member in interlocked engagement with said plunger for positively holding said plunger in unarmed position until projectile acceleration ceases.
13. In a projectile fuse, the combination 35 with a fuse body comprising two separable parts one of said parts carrying an integral gaine said parts being provided with oppositely disposed axial bores, of a detonating mechanism housed within said bores and comprising a detonator pellet, a coöperating plunger, and a single member in interlocked engagement with said plunger for positively holding said plunger in unarmed position until projectile acceleration ceases.
- 40 14. In a projectile fuse, the combination with a detonating plunger, of a split sleeve surrounding and in interlocked engagement with said plunger and provided with a series of longitudinal grooves to form the 45 sleeve into connected segments the weights of which are pre-determined in accordance with the rotative velocity of a projectile at

the muzzle of a gun in connection with which it is used.

15. In a projectile fuse, the combination 55 with a detonating plunger, of a split sleeve surrounding and in interlocked engagement with said plunger and provided with a series of internal longitudinal grooves to form the sleeve into connected segments the 60 weights of which are pre-determined in accordance with the rotative velocity of a projectile at the muzzle of a gun in connection with which it is used.

16. In a projectile fuse, a detonating 65 plunger having an undercut flange adapted to support and for engagement with the beveled end of a split locking sleeve.

17. In a projectile fuse, a split locking sleeve provided with a series of longitudinal 70 grooves to form a sleeve into connected segments, the weights of which are pre-determined in accordance with the rotative velocity of a projectile at the muzzle of a gun in connection with which it is used, said 75 sleeve having a beveled end adapted for engagement with the undercut flange of a supporting detonating plunger.

18. In a projectile fuse, a split plunger locking sleeve provided with a series of longitudinal grooves to form the sleeve into connected segments the weights of which are pre-determined in accordance with the rotative velocity of a projectile at the muzzle of a gun in connection with which it is 85 used.

19. In a projectile fuse, a split plunger locking sleeve provided with a series of internal longitudinal grooves to form the sleeves into connected segments the weights 90 of which are pre-determined in accordance with the rotative velocity of a projectile at the muzzle of a gun in connection with which it is used.

20. In a projectile fuse, the combination 95 with a fuse body, of a plunger within the body, and a single non-resilient member in interlocked engagement with said plunger for positively holding said plunger in unarmed position until projectile acceleration 100 ceases.

In testimony whereof, I have signed my name to this specification.

WILFORD JUDSON HAWKINS.
